UNITED STATES PATENT OFFICE.

JAMES T. PRICE, OF LINCOLN, ILLINOIS.

SEWING-MACHINE LAMP BRACKET.

Application filed October 8, 1923. Serial No. 667,190.

To all whom it may concern:

Be it known that I, JAMES T. PRICE, a citizen of the United States, residing at Lincoln, in the county of Logan and State 5 of Illinois, has invented certain new and useful Improvements in Sewing-Machine Lamp Brackets, of which the following is a specification.

This invention pertains to lamp brackets 10 for sewing machines, and the object of the invention is to provide in a simple and practical form, an adjustable bracket attachable to the arm of a sewing machine and adapted to hold an electric lamp in suitable position 15 for throwing the light upon the work.

In the drawing

Figure 1 is a reduced perspective view showing the attachment in place on a machine;

20 Figure 2 is a top view of the assembled bracket, post and clamp;

Figure 3 is a front view of the assembled bracket, post and clamp;

25 Figure 4 is a side view of the assembled bracket, post and clamp;

Figure 5 is a detail of the lamp supporting post;

Figure 6 is a blank showing the form of the bracket as stamped out of sheet metal.

30 The invention comprises a bracket 1 formed in any suitable manner, as by stamping from sheet metal. This bracket includes a relatively long and flat top strip 2, having anchor prongs 3 at the end thereof, an integral and perpendicular flat connecting strip 4, a relatively short, integral, flat bottom strip 5 extended back parallel to the top strip, and ending in an outwardly or downwardly turned anchor tab 6. Clamp 35 fingers 7 are extended back inwardly from the connecting strip 4 and are pierced with holes 8 to accommodate a bolt 9 passed therethrough, the bolt having a thumb nut 10 at the end thereof to complete the clamp.

40 Holes 11 are pierced through the top and bottom strips 2 and 5, and are aligned between the clamp fingers 7. A lamp supporting post 12, reduced at the points 13 and 14 to form shoulders, is passed down 45 through the holes 11, and is seated therein upon the shoulders 13 and 14 for rotative movement. Screw holes 15 are pierced through the ends of the prongs 3 and 50 through the tab 6. The clamp is positioned

horizontally upon the arm 16 of the sewing 55 machine 17, and perpendicularly thereto at the front side thereof, and with the prongs 3 embracing the spool spindle 18; and is secured in place by set screws 19 passed through the holes 15 and into the said arm 16. 60 The post 12 has an upwardly extended shank 20, through which the cord hole 21 is formed. The conventional electric lamp 22 is soldered or otherwise suitably secured at the point 23 to the side of the shank 20 with the lamp 65 cord 24 passed through the hole 21. The lamp 22 is disposed horizontally along the front of the arm 16 and so as to throw the light down directly upon the work. The lamp may be adjusted back and forth in a 70 horizontal plane, turning upon the post 12, and when in the desired position, may be clamped tight by turning up the thumb nut 10.

75 While I have herein described a certain specific manner and method of constructing and assembling the elements of my invention, it is understood that I may vary from the same in minor details, not departing from the spirit of my invention, so as best to 80 construct a practical device for the purpose intended, as defined in the appended claims.

I claim:

1. A bracket of the kind described, adapted 85 for attachment to the arm of a sewing machine and for supporting an electric lamp in operative position at the front of the sewing arm, the said bracket comprising a top strip having anchor prongs adapted to embrace the spool spindle, a perpendicular connecting strip, an inwardly extended bottom strip, and a downwardly turned anchor tab; the said top and bottom strips having aligned holes adjacent the connecting strip, and a lamp supporting post rotatively 90 mounted through the said aligned holes; and means for securing the bracket to the sewing machine arm.

2. A bracket of the kind described, adapted 100 for attachment to the arm of a sewing machine and for supporting an electric lamp in operative position at the front of the sewing arm, the said bracket comprising a top strip having anchor prongs adapted to embrace the spool spindle, a perpendicular connecting strip, an inwardly extended bottom strip, and a downwardly turned anchor tab; the said top and bottom strips having 105

aligned holes adjacent the connecting strip, and a lamp supporting post rotatively mounted through the said aligned holes; means for securing the bracket to the sewing machine arm; and a clamping element for locking the lamp supporting post in any adjusted position.

In testimony whereof I affix my signature.

JAMES T. PRICE.
